UNITED STATES PATENT OFFICE

160,238

TOILET KIT

Thea Worcester, Chicago, Ill.

Application June 14, 1949, Serial No. 3,276

Term of patent 7 years

(Cl. D87—5)

To all whom it may concern:

Be it known that I, Thea Worcester, a citizen of the United States, and resident of Chicago, in the county of Cook and State of Illinois, have invented a new, original, and ornamental Design for a Toilet Kit, of which the following is a specification, reference being had to the accompanying drawing, forming part thereof, wherein:

Fig. 1 is a perspective view of a toilet kit embodying my new design, the opposite side and end being the same in appearance as the side and end shown; and

Fig. 2 is a perspective view illustrating the toilet kit in an open position.

The characteristic feature of my design for a toilet kit resides in the continuous strap extending around three sides thereof, said strap being substantially the same in width as is the kit in depth and being held in spaced relation by

attachment at the two front corners of the kit.

I claim:

The ornamental design for a toilet kit, as shown and described.

THEA WORCESTER.
